UNITED STATES PATENT OFFICE.

SIMON B. STORER, OF SYRACUSE, NEW YORK

VOLTAGE-REGULATOR.

No. 854,128.

Specification of Letters Patent.

Patented May 21, 1907.

Application filed October 23, 1906. Serial No. 340,234.

To all whom it may concern:

Be it known that I, SIMON B. STORER, of Syracuse, in the county of Onondaga, in the State of New York, have invented new and useful Improvements in Voltage-Regulators, of which the following, taken in connection with the accompanying drawings, is a full, clear, and exact description.

This invention relates to certain improvements in voltage regulators for electrical distributing systems including therein any translating devices or loads, portions of which are adapted to be thrown on or off at will, thereby causing a drop or rise of the voltage in other parts of the system.

It is clear that if the initial current from the source of energy is transformed to give a predetermined voltage in certain translators or loads in one part of the system when the load in another part of the system is on, then, when the latter load is thrown off, the voltage in other parts of the system will rise above the predetermined value, due to transformer and line losses. On the other hand, if the initial current is transformed to give a predetermined voltage in one part of the system when the load in another part of the system is off, then, when such load is thrown on, there will be a corresponding drop of voltage in other parts of the system. For example, in an electric lighting system for arc and incandescent lamps, where current for both arc and incandescent lamps is obtained from one main transformer supplied from a high voltage transmission line, if the transformer connections were adjusted to give the proper voltage in the incandescent circuit when the arc circuit is closed, then, when the arc circuit is opened the voltage in the incandescent circuit will be too high. Or, if the transformer was adjusted to give the desired voltage in the incandescent circuit when the arc circuit is opened, then, when the arc circuit is closed, the voltage in the incandescent circuit will be too low.

My object, therefore, is to introduce into the system an automatic voltage regulator which will, in a single step, approximately compensate for any excessive change of voltage in the system due to a sudden or considerable change of load in any part of such system. In other words, the specific purpose of my invention is to introduce by the use of suitable transformers in the main circuit, certain predetermined voltage values sufficient to compensate for the drop or rise in voltage

due to any considerable change in load and to automatically throw such voltage values into the distributing system through the medium of an electric switch which is brought into action by such changes in load of the circuits of the system which may produce an excessive change of voltage in other parts of the system, without necessarily opening the main circuit. For example, assuming that in a 2300 volt circuit or system it is desired to maintain a voltage of say 2200 and that the throwing on of a certain load would cause a drop of say 300 volts, and the throwing off would cause a similar rise of voltage, it is evident that if by means of improved regulator say 100 volts could be subtracted from the circuit when the load was off and 200 volts added to it when the load was on, the voltage in such system or circuit would remain practically at its predetermined value of 2200, while without such regulator action it would range from 2000 to 2300 volts.

In the drawings, Figure 1 is a diagrammatic view of an electric lighting system including therein my improved voltage regulator. Figs. 2 and 3 are diagrammatic views of modified forms of portions of the system seen in Fig. 1, the series transformer shown in Fig. 1, being replaced by a single or an auto-transformer in Fig. 2, while in Fig. 3 the coils are entirely omitted and substituted by reverse connections to the switch.

This lighting system comprises a main circuit —1— deriving current from a source of electric energy as a dynamo —2— through the medium of a step down transformer —3— which supplies current to any number of circuits as an arc lamp circuit —4— and an incandescent lamp circuit —5— through the medium of transformers 6 and 7. The primary circuits of the transformers —6— and —7— are provided with suitable switches 8 and 9 respectively for controlling the operation of the translating devices as arc lamps —10— and incandescent lamps —11— which are connected respectively in the circuits —4— and —5—. It is now evident that with the elements just described, if the transformers are adjusted to give the desired voltage in the incandescent circuit —5— when the load of the arc circuit is off, as shown, then, when the load in the arc circuit is thrown on by the closing of the switch —8— it causes a drop of voltage in the circuit —1— due to line losses and transformer losses, and a corresponding drop in the incandescent circuit —5— below

the predetermined value, while on the other hand, if the transformers —3— and —7— are adjusted to give the desired voltage in the incandescent circuit —5— when the load in the arc circuit is on, then, when such load is thrown off it will cause a rise of voltage in the circuits —1— and —5— in excess of the predetermined value. This, of course, results in poor service in the translating devices in the circuit —5— and in order to overcome this, and to maintain a practically uniform voltage value in the circuits —1— and —5— I have introduced into the circuit —1— a shunt transformer —12— and a series transformer —13—, and have also introduced into the arc circuit —4— the winding of a solenoid —14—.

The primary winding of the transformer —12— is connected across the circuit —1— and the opposite ends of its secondary winding are connected by wires —15— and —15'— to a pair of terminals —16— of an electric switch —S—. This switch is provided with an additional pair of terminals —17—, one of which is electrically connected by a wire —18— to an intermediate point substantially midway between the ends of the secondary winding of the transformer —12— while the other terminal is electrically connected by a wire —18— to the end of said secondary winding to which the wire —15'— is connected. The switch —S— is also provided with a pair of movable contact arms —20— which are connected to the plunger —14— through the medium of an arm —21— and plunger rod —22—, the arm —21— being provided with a slot —23— to receive a pin —24— on the lower end of the rod —22—, to permit the plunger to move freely a limited distance, before actuating the switch arms —20—. The switch arms —20— are normally in electrical contact with the lower terminals —17—, being forced to this position by the gravity of the solenoid plunger, when said solenoid is de-energized by opening the arc lamp circuit, said switch arms being also electrically connected by wires —25— and —25'— to the terminal ends of the primary winding of the series transformer —13—, and, therefore, this primary winding is normally in electrical connection with the low voltage or secondary winding of transformer —12—.

It will be observed that the connections of the secondary winding of the transformer —12— with the lower and upper terminals of the switch are reversed so as to reverse the voltage impressed on the series transformer —13— when the switch is operated.

When the load in the circuit —4— is cut out, thereby de-energizing the solenoid —14— allowing the switch to close the circuit through the terminals —17—, a portion of the voltage, in this instance substantially half, in the secondary winding of the trans-

former —12— is thrown into the primary winding of the series transformer —13— to oppose the flow of the current in the circuit —1—, and thereby cuts down its voltage by an amount corresponding approximately to 70 one third the rise of voltage caused by cutting out the load. On the other hand, when the load in the arc circuit —4— is thrown on thereby energizing the solenoid —14—, the switch is operated to break contact with the terminals —17— and to close the circuit through the terminals —16— thereby adding the full voltage of the secondary winding of the winding transformer —12— through the primary of the series transformer —13— to the 80 circuit —1— to compensate for approximately two thirds of the drop of voltage in the system caused by throwing on such load. For example, assuming that the transformer —13— is adjusted with a one to one transformation ratio, and that the transformer —3— is adjusted to give 2300 volts at no load in the circuit —1—, and that the transformer —12— is connected to deliver 200 volts to the terminals —16— and —100 volts 90 to the terminals —17—, then, when the arc circuit —4— is thrown on causing a drop of 300 volts in the transformer —3— and circuit —1—, and also energizing the solenoid —14—, the plunger of said solenoid is instantly drawn upwardly and operates the switch —S— to open the circuit at the terminals —17— and to close the circuit through the terminals —16—. Approximately the full 200 volts is thereby thrown into the primary winding of the series transformer —13— and added to the circuit —1— to compensate partially for the drop of voltage caused by throwing on the arc circuit, and to bring the voltage back to approximately 105 2200 in the circuit —1—. On the other hand, when the load in the arc circuit is thrown off by opening the switch —S—, the solenoid —14— is de-energized allowing its plunger to drop by gravity, which in turn operates the switch —S— to throw the arms —20— out of contact with the terminals —16— and into contact with the terminals —17—, thus throwing a reverse voltage of approximately 110 100 volts from the secondary of the 115 transformer —12— into the primary of the transformer —13— to oppose the voltage in the circuit —1— thereby lowering it to approximately 2200 volts. By this means, I am enabled to maintain a practically uniform 120 voltage of 2200 in the circuit —1— and a proportionate voltage in other parts of the system, as the incandescent circuit —5— deriving current therefrom; and it is clearly evident that this regulator may be used in 125 other relations than that in a lighting system and that the voltage may be raised or lowered any amount desired, or, the same operation carried out in any circuit of any desired voltage by making due provision or adjustment 130

in the windings and connections of the transformers —12— and —13—.

The series transformer —13— may, in some instances, be omitted, as in circuits of comparatively low voltage and amperage, the wires —25— and —25'— then being connected to the terminals —26— and —26'—, where one side of the circuit —1— has been cut or broken as in Fig. 3. The double coil series transformer —13— may also be replaced by a single coil or an auto-transformer if desired, (Fig. 2.)

It is also evident that the regulator may be used in connection with circuits of any number of phases by providing a suitable number of transformers, solenoids and switches.

What I claim is:

1. A system of electrical distribution including therein two transformers, and automatic means for throwing the whole or part of the transformed voltage of one transformer into the other transformer.

2. In combination with an electric circuit including therein the primary winding of a shunt transformer and the secondary winding of a series transformer, and automatic means for throwing the whole or part of the transformed voltage of the first named transformer into the series transformer.

3. In a system of electrical distribution an electric circuit including therein the load of one or more translation devices, means to cut said load into and out of circuit, and separate means brought into action by the opening and closing of said circuit for automatically introducing a predetermined voltage into the system.

4. A system of electrical distribution including therein the primary winding of a shunt transformer and secondary winding of a series transformer, a translating device deriving current from said system, means for cutting said translating device into and out of electrical connection with said system, an electric switch connected to the secondary

winding of the shunt transformer and to the primary winding of the series transformer and electrically operated means connected in circuit with the translating device, for operating said switch to change the connections in the circuits between the secondary winding of the shunt transformer and the primary winding of the series transformer when the translating device is energized or de-energized.

5. A system of electrical distribution including therein the load of one or more translating devices adapted to be thrown on or off whereby a change of voltage is effected in other parts of the system, means to cut said load into and out of circuit, and automatic means brought into action by the opening and closing of said circuit for automatically introducing a predetermined voltage into the system to compensate in a single step for such change of voltage.

6. In an electrical distributing system including therein any load adapted to be thrown on and off, thereby causing drop or rise of voltage in other parts of the system, a transformer having its primary winding deriving current from said system, a series transformer having its secondary winding in said system, the first named transformer being adapted to produce a voltage in its secondary winding substantially equal to the drop voltage in the system when the load is thrown on, and means brought into action by the closing of the circuit through said load for throwing the voltage from the secondary winding of the first named transformer into the primary winding of the series transformer, thereby adding to the system a voltage substantially equal to the drop.

In witness whereof I have hereunto set my hand this 15th day of September 1906.

SIMON B. STORER.
